UNITED STATES PATENT OFFICE.

WALTER DEWITT KEMP, OF NEW YORK, N. Y.

TOY GRENADE.

1,348,224.

Specification of Letters Patent.

Patented Aug. 3, 1920.

Application filed July 11, 1919. Serial No. 310,108.

To all whom it may concern:

Be it known that I, WALTER DEWITT KEMP, a citizen of the United States, residing at New York, in the county of New York and 5 State of New York, have invented certain new and useful Improvements in Toy Grenades, of which the following is a specification.

This invention relates to a toy, and has 10 for its object the provision of a novel toy made in the form of a base ball, adapted to be thrown against a surface in a manner whereby, upon the impact of a certain peripheral portion, a detonation is produced 15 without injury to the ball.

Another object is to produce a toy particularly appropriate for boys as an outdoor sport by means of which the muscles of the hand and fingers may be developed 20 and skill acquired in accuracy of handling a ball, particularly with reference to the manipulation of the fingers around the ball and the skilful grasping, controlling and hurling the ball in such a manner as to 25 cause a predetermined point thereon to make contact with the surface struck. It is well known that professional base ball pitchers acquire and make use of such fineness of control. The invention affords a useful and 30 ready means to the boy of measuring or determining this ability.

A further object is the provision of a ball having a vari-colored exterior in each colored section of which is engaged a paper 35 disk containing materials adapted to detonate upon concussion and to emit a correspondingly colored smoke or gas therefrom.

These and other objects are accomplished by means of such structure and novel arrangement of parts as are hereinafter described and shown in the accompanying drawings, which form a part of this disclosure, and which are to be considered as 40 illustrative and descriptive only and not as 45 restrictive or limitative, and in which:

Figure 1 is a perspective view illustrating the ball and results attained thereby;

Fig. 2 is an elevational view of a ball made in accordance with the invention;

Fig. 3 is an enlarged fragmentary plan view of the same;

Fig. 4 is a partial sectional view thereof, taken on the line 4—4 of Fig. 3; and

Fig. 5 is a similar fragmentary sectional view showing a modified form of construction.

Similar numerals of reference indicate corresponding parts in the several views.

Referring to the drawings in detail, the numeral 10 will be seen to designate a sidewalk, and 11 the wall of a building or the like, presenting a rigid surface against which the hand ball, generally designated by the numeral 12, may come in forcible contact, when thrown. These balls are preferably made of a resilient wood or of rubber or fiberoid and of the size of an ordinary base ball. The ball may be constructed with a single detonating unit, but in the adaptation illustrated, three units are shown and 70 the exterior of the ball is colored red, white and blue, as indicated by the numerals 14, 15 and 16, forming tri-colored segments as indicated. This permits of a game being played, which will be referred to later. 75

Secured centrally in each of the several segments are metal plates or anvils 17, the same being slightly below the peripheral surface of the sphere and held therein by undercut edges, tacks, spurs, cement, or the like. 80 In the modification shown in Fig. 5, in place of the plate 17, the head 21 of a barbed brad or nail 22 may be used as the anvil element, if wood is employed, with equally effective results. Disposed over these anvil elements 85 are leaf-like cover plates 18 formed with angularly extending elements 19 adapted to be forced radially into the material of the ball in the manner of brads or spurs, or, if a rubber ball, solid or hollow, be used, the 90 elements 19 may be suitably cemented, whereby the cover plates are resiliently but permanently secured. Between the fixed plates 17 and the cover plates 18 are recesses 95 adapted to receive disks or paper capsules containing material adapted to detonate by the percussion of the ball with a surface, affording considerable noise. The edges of the cover plates 18, as well as of the anvil elements 17, may be curved slightly, in 100 order to assist in holding the capsules in place. The material in the capsules is also adapted to liberate colored smoke or gas, when exploded. Thus when the ball is thrown against a surface, a report takes 105 place accompanied by the liberation of colored smoke, the smoke corresponding in color to the color of the segments of the ball in which the caps are confined. It is obvious that the ball must 110 be thrown with such accuracy and precision that the relatively small area presented by

the resilient cover plate 18 is the part of the ball which is caused to come in contact with the surface struck, or the noise and smoke making property of the ball remains quiet.

- 5 The preferred manner of playing a game with the adaptation illustrated is to load the three recesses with paper caps which produce red, white and blue smoke, respectively.
- 10 Throw the ball on the sidewalk so as to cause the cover plate 18 holding the cap producing the red smoke to strike the sidewalk and explode the cap; catch the ball as it rebounds, and quickly and with such accuracy of
- 15 manipulation of the hand and fingers and before the red smoke has become dissipated, throw it again to the sidewalk, this time in such manner as to cause the cap containing the white smoke to explode; similarly catch
- 20 the ball on the third rebound and as quickly as possible throw it again to the sidewalk in such a manner that the cap containing the blue smoke will explode. If these several actions are skilfully performed, the three
- 25 explosions occur in sufficiently quick succession so that the red, white and blue smoke will intermingle and blend, and form the colors of our national emblem. A pyrotechnic display is thus afforded which ma-
- 30 terially enhances the novelty of the toy. The game is of a four-fold nature, viz: to throw the ball accurately enough so that the proper cap is exploded each time in order that red, white and blue smoke may follow in se-
- 35 quence; to catch the ball; to throw the ball quickly enough so that all three caps will be exploded before the first smoke has become dissipated; and finally, to see who forms the nearest approach to the shape and
- 40 appearance of the flag through the blending of the liberated smoke waves as they become dissipated in the air.

New caps are entered into the recesses as they become exhausted, and as new ones are

45 inserted they push the remains of the old ones out.

It should be noted that any selective combination of colors may be thus produced, such as the national colors of any foreign

50 country, or the colors of a school, fraternity, club, etc., a ball containing a larger number of the detonating units being used, if desired; and that the free end of the cover plate 18 may be curved slightly inwardly,

55 in order to protect it somewhat, and a small groove or depression may extend in the surface of the ball, immediately thereunder, to accommodate the curved end of the cover plate, upon concussion. Obviously, minor

60 modifications may be made within the scope of the invention.

The various elements may be constructed in any suitable size and shape and they may be made of any selective kind of material,

so long as the various members of the combination coact and coöperate to perform the functions and produce the results contemplated, without departing from the spirit of the invention.

I claim:

1. An unrestrained hand ball, comprising a sphere and means in combination therewith for producing noise and emitting smoke upon concussion of a predetermined point on the surface of the ball with a solid
- 70 surface.
- 75 2. A ball comprising a free unconfined sphere, a detonating unit engageable at a definite point on the circumference of said sphere, and means for holding said detonating unit in close relation to the surface of said sphere, said holding means permitting the removal of said unit.
- 80 3. A handball comprising a sphere having a substantially non-protuberant surface, an anvil element embedded below the surface of the sphere, and a resilient clip extending over said anvil element presenting a space
- 85 therebetween.
4. A handball comprising an unconfined, resilient hollow sphere having a substantially non-protuberant surface, a metallic anvil element secured in the surface of said sphere, and a spring plate secured in said surface and extending over said anvil element, forming a space therebetween adapted to receive a capsule containing fulminating material, said plate and said anvil element adapted to hold said capsule in confinement normally and to detonate the same upon con-
- 90 cussion of said plate on said sphere with a solid object, said plate being substantially flush with the surface of the sphere.
- 95 5. A hand ball comprising an unconfined solid sphere having a substantially non-pro-
- 100 tuberant surface, a metallic anvil element inserted in the surface of said ball, a plate secured to the peripheral surface of said sphere extending over said anvil element forming a space therebetween, and a paper
- 105 capsule containing fulminating material dis-
- 110 posed between said plate and anvil whereby it is held in confinement and detonated upon the concussion of said plate on said sphere with a surface.
- 115 6. A hand ball comprising a sphere, its surface being divided into colored segments, metallic anvil elements inserted centrally in each of said segments, spring plates secured to the peripheral surface of said sphere ex-
- 120 tending over said anvil elements forming a space therebetween, and paper capsules containing fulminating material disposed be-
- 125 tween said spring plates and anvils whereby said capsules are held in confinement and detonated upon the concussion of said plates on said sphere with a solid surface.
7. A toy comprising a hand ball having a

several-colored segmental exterior, said ball containing a plurality of recesses, metallic anvils fixed in said ball at the bottom of the mentioned recesses, metallic cover plates disposed over said anvils, means for engaging said cover plates to the surface of said ball, and paper capsules disposed below said cover plates upon said anvils, said capsules being filled with a material adapted to detonate and to produce diversely colored smoke

or gas upon percussive contact of said cover plates with a rigid object.

In testimony whereof, I have signed my name to this specification, in the presence of witnesses, this 10th day of July, 1919.

WALTER DEWITT KEMP.
